UNITED STATES PATENT OFFICE.

LUIGI OLIVERO, OF GENOA, ITALY.

DEVICE FOR LOCKS.

Application filed October 12, 1922. Serial No. 594,163.

To all whom it may concern:

Be it known that I, LUIGI OLIVERO, mechanical engineer, subject of the King of Italy, and residing at 31 Via XX Settembre, Genoa, Italy, have invented certain new and useful Improvements in Devices for Locks, of which the following is a specification.

This invention relates to improvements in locks and has for its object to provide a lock structure wherein the unauthorized displacement of the bolt of the lock is prevented by a plurality of pivotally mounted and key-controlled locking members co-acting with segmental flanges provided internally of the lock casing.

A further object is the provision of a lock of this type wherein it is impossible to withdraw the key without having first projected the bolt to operative position.

In the accompanying drawing wherein an approved embodiment of the invention is illustrated;

Figure 1 is a vertical sectional view of a lock showing the key withdrawn from the barrel.

Figure 2 is a view similar to Fig. 1 showing the key inserted in the barrel.

Fig. 3 is a transverse sectional view of the key taken on the line O—O of Figure 1.

Fig. 4 is a fragmentary sectional view through the lock and casing showing the barrel and locking members in elevation.

Figure 5 is a transverse sectional view on the line X—X of Fig. 4.

Referring to the drawings in detail the numeral 9 indicates the lock casing, the opposed walls of which are apertured and rotatably receive the barrel 3 having a longitudinal bore 3^a for the reception of the key 2. The usual bolt 8 is slidably mounted in the casing 9 and is adapted to be projected therefrom incident to rotary movement of the barrel 3 in one direction by a pinion 7 keyed on the barrel 3 meshing with teeth 7^a on the bolt 8.

The exterior portion of the barrel 3 lying within the lock casing 9 is provided with pairs of radiating ears 3^a, the portion of the barrel lying between the ears of each pair being cut away to provide slots 3^b through which may work the locking members 1. The locking members are pivotally mounted at 4 between the pairs of ears 3^a and they are provided with shoulders 10 which normally

project into the bore 3^a of the barrel 3 and are adapted to be actuated by the key 2, the locking members being normally retained in inwardly projected position with the shoulders 10 yieldably obstructing the insertion 60 of the key 2 by springs 5 carried by the pinion 7.

The locking members 1, when the bolt 8 is projected, and the key 2 is withdrawn, normally occupy positions in slots 11 formed 65 radially in a circular flange 6 forming an integral part of or secured to the adjacent wall of the lock casing 9 so that it is impossible to rotate the barrel 3 to effect retraction of the bolt 8. However, in order 70 that the barrel 3 may be revolved in order to retract the bolt upon insertion of the proper key 2 by an authorized person, the locking members 1 are provided with recesses 12 which, when registered with the 75 slots 11 in the flange 6, permit the barrel 3 and the locking members 1 to revolve as a unit.

In order to establish a non-rotatable connection between the key 2 and the barrel 80 3, and also to effect the proper displacement of the locking members 1 whereby to move the recesses 12 thereof into registration with the slots 11, the key shank is provided with a plurality of longitudinal slots 13 in which 85 the shoulders 10 of the locking members slide during insertion of the key and the depth of these slots 13 is such that, when the key is properly inserted in the barrel 3, the locking members are displaced from 90 the position shown in Fig. 1 to that shown in Fig 2 where the recesses 12 of the locking members register with the slots 11 in the flange 6 and thus upon turning the key 2 the barrel 3 is moved therewith and the 95 pinion 7 meshing with the teeth 7^a of the bolt 8 may retract the latter.

The depth of the grooves 13 decreases towards the extremity of the key shank thereby forming a plurality of cam faces 14, which are designed to prevent the removal of the key 2 from the barrel 3 except when the bolt 8 has been either fully projected or fully retracted, it being impossible 100 to remove the key with the bolt 8 in an intermediate position due to the fact that the flanges 6 occupy the recesses 12 in the locking members 1 and prevent further outward swinging movement of the locking members on their pivot pins 4, the cam 110

faces 14 thus coacting with the shoulders 10 of the locking members to prevent the removal of the key.

In the operation of the improved lock, 5 when the bolt 8 has been fully projected by the turning movement of the key 2 and the barrel 3, the key is withdrawn from the barrel and the springs 5 acting upon the locking members 1, move the latter inwardly 10 through the slots 11 and the flange 6 and the slots 3^b in the barrel 3 and coacting with the segments of said flange 6, prevent such rotary movement of the barrel 3 as would effect retraction of the bolt 8. 15 It is impossible to withdraw the key 2 from the barrel unless the locking members 11 are in such position as to enter the slots 11 due to the fact that the cam faces 14 will engage the shoulders 10 of the locking 20 members and obstruct the outward movement of the key, said locking members being prevented from swinging outwardly, due to the engagement thereof with the flange 6. When it is desired to retract the 25 bolt the key 2 is inserted in the barrel 3 and the locking members 1 coacting with the walls of the grooves 13 are swung outwardly to such positions that the recesses 12 therein register with the slots 11 and it 30 is thus possible upon turning the key of the barrel to retract the bolt.

Having now particularly described and ascertained the nature of my said invention, and in what manner the same is to be performed, I declare that what I claim is:

1. A lock comprising a casing, a bolt

movable in said casing, a rotatable barrel journaled in said casing coacting with said bolt to project and retract the latter and having a longitudinal bore spaced projections carried by the casing, pivoted locking members carried by the barrel and normally occupying a position between the projections of the casing whereby to prevent rotation of the barrel, shoulders on said locking members normally projecting into the bore of said barrel, means normally tending to move the locking members to a position wherein their rotary movement about the axis of the barrel is obstructed by said spaced projections, means adapted, when said locking members are moved to a predetermined position with respect to the barrel, to permit said barrel to rotate about its axis, and a key adapted for insertion in the bore of said barrel for moving said locking members to said predetermined position.

2. A lock as claimed in claim 1 having a key provided with a plurality of grooves adapted to receive the shoulders of the locking members and that the inner walls of the grooves are provided adjacent the extremity of the key with cam faces adapted to prevent removal of the key except when the bolt is fully retracted or projected.

In testimony whereof I affix my signature in presence of two witnesses.

LUIGI OLIVERO.
